UNITED STATES PATENT OFFICE.

WILLIAM FONDILLER, OF NEW YORK, N. Y., ASSIGNOR TO WESTERN ELECTRIC COMPANY, INCORPORATED, OF NEW YORK, N. Y., A CORPORATION OF NEW YORK.

LOADING UNIT.

Application filed September 3, 1918. Serial No. 252,417.

To all whom it may concern:

Be it known that I, WILLIAM FONDILLER, a citizen of the United States, residing at New York city, in the county of New York, State of New York, have invented certain new and useful Improvements in Loading Units, of which the following is a full, clear, concise, and exact description.

This invention relates to the loading of 10 telephone systems, and more particularly to systems including two physical or side circuits and a derived or phantom circuit.

In Olsson and Pleijel Patent No. 1,148,792, there is described a loading unit for this purpose, this unit comprising two coaxially arranged toroidal cores, one for each physical circuit, each half of each core being occupied by one of the line windings for its physical circuit. The directions of the 20 windings in each core are such that when they are traversed by a current in the phantom circuit, the corresponding fluxes in the two halves of the core are opposed at the diametrically opposite points of the core between the windings, and therefore emerge from the core and complete their circuits externally thereof. Bridges of low reluctance extend between the cores at their diametrically opposite points and afford a ready 25 path from one core to the other for the external flux, whereby the loading of the phantom circuit is materially increased. The ideal operation of such a loading unit involves the assumption that there is no passage of flux from one core to another, due to 30 current in the physical or side circuits. This, however, is not actually the case, since some of the side circuit flux in each half of each core will find its way through the 35 bridges to the other core, and consequently cause more or less cross-talk in the circuit whose windings are on that core.

One object of this invention is, therefore, to provide a loading unit, of the general 40 type above described, but in which there will be little, if any, passage of flux produced by current in one physical circuit to the core belonging to the other physical circuit. This is accomplished by means of a shunt 45 of low reluctance which diverts from each core the undesirable flux from the other core.

Further objects and advantages of the invention will be apparent from the follow-

ing detailed description, read in connection with the accompanying drawing, in which Fig. 1 is a schematic representation of a telephone system equipped with the improved loading unit; and Fig. 2 is a perspective view of a loading unit constructed according to this invention, with the windings and part of one core removed to show the details.

Referring to Fig. 1, the two pairs of line conductors 1, 2 and 3, 4 provide two physical 65 circuits 5 and 6 and a derived phantom circuit 7. One of the loading units common to all three circuits is shown at 10, and comprises two toroidal cores 11 and 12, of suitable magnetic material, arranged in physical 70 circuits 5 and 6, respectively. The opposite halves of core 11 carry the windings 13 and 14 which form parts of the line conductors 1 and 2. Each of these windings covers slightly less than half of the core, the diametrically opposite portions 15 and 16 of the core being uncovered. Similarly, the core 12 is provided with the windings 17 and 18 for the line conductors 3 and 4, and with diametrically opposite uncovered portions 75 19 and 20. As shown in Fig. 2, the two cores 11 and 12 are co-axially arranged one above the other with yokes 21 and 22 of low reluctance, connecting the diametrically opposite portions 15 and 19, and 16 and 20, respectively, as described in the Olsson and Pleijel patent referred to above.

In accordance with this invention the yokes 21 and 22 are connected by a bridge 24 of low reluctance, the yokes 21 and 22 and the bridge 24 being preferably parts of an integral structure and of such dimensions that they will afford ready paths for all the flux that may reach them from the cores. The yokes and bridges are desirably formed 90 of material of high permeability, in order that the space occupied by them, and especially the distance by which the adjacent ends of the windings on each core, are separated shall be as small as practicable. The 100 operation of a system equipped with a loading unit embodying this invention is as follows:

With current flowing in the phantom circuit the portions 15 and 16 of the core 11, 105 19 and 20 of core 12 will be points of considerable flux emergence, since the fluxes in the two halves of each core will be opposed.

The windings of the cores are, however, so arranged that points 15 and 19 will be of opposite polarities and points 16 and 20 will likewise be of opposite polarities, points 16 and 19 and likewise points 15 and 20 being of the same polarities so that there will be flux between the cores in one direction through the yoke 21, and a substantially equal flux in the opposite direction through the yoke 22. Under these circumstances, the mid-portions of the yokes will be at practically the same magnetic potential, that is, intermediate the potentials of the ends of the yokes, so that there will be substantially no magnetic flux through the bridge. The yokes 21 and 22 perform the same function as that performed by the yokes in the Olsson and Pleijel device, that is, by affording paths of low reluctance between the cores for the emergent flux, they materially add to the loading of the phantom circuit.

Current flowing in the physical circuit will produce fluxes in the same direction in both halves of the core 11; but since the two cores are connected by the low reluctance yokes 21 and 22, and since these yokes must be wide enough to carry the phantom flux, there is presented, between the adjacent ends of the two windings on the core, an appreciable area from which side circuit flux may pass from the core into the yokes. The core 12 being of low reluctance, offers a path through which this emergent side circuit flux would, unless prevented, complete the portion of this circuit externally to the core 11. If the flux followed this path, cross-talk would be produced in the side circuit 6 by reason of the currents induced by the interlinkage with the flux in the windings of the core 12. The bridge 24 prevents this by offering a magnetic shunt through which the emergent side circuit flux is diverted from core 12, for there is not, as is the case with the phantom flux, a corresponding balancing flux in the core 12 to equalize the magnetic potentials at the mid-points of the yokes.

Similarly, the side circuit flux escaping from core 12 at 19 and 20 does not reach the core 11, but is shunted through the bridge 24.

In order to avoid loss through eddy currents, the yokes 21 and 22 and the bridge 24 may be either laminated, in accordance with well-known practice, or formed of insulated particles of finely divided magnetic material, molded by pressure into the desired form.

In some instances it may be desirable to reduce the phantom circuit loading, as compared with the side circuit loading. This can be accomplished by means of the present invention by connecting the wind-

ings on the cores to the line conductors, so that current in the phantom circuit produces the same polarity at 15 and 19, and the opposite polarities at both 16 and 20. Under these circumstances the phantom current flux leaving each core, instead of passing by way of the yokes 21 and 22 to the other core, will be shunted through the bridge 24, and so prevented from reaching the other core. In this case the cross-section and material of the bridge will be such as to increase its permanence sufficiently to enable it to carry the phantom current flux from both of the cores of the loading unit.

As the ratio of phantom circuit loading to side circuit loading depends upon the percentage of the flux that is diverted through the bridge 24, that is, on the material and cross-section of the bridge, this invention affords a means for providing a loading unit in which this ratio has a value selected in accordance with the circumstances under which it is to be used.

What is claimed is:

1. A loading unit core structure comprising two toroidal core members, means providing paths of low reluctance between said members, and a low reluctance shunt connecting said paths. 90
2. A loading unit core structure comprising two toroidal core members, and a bridge of low reluctance forming a magnetic path between diametrically opposite portions of each of said core members. 95
3. A loading unit core structure comprising two toroidal core members, yokes of low reluctance between said members at diametrically opposite points, and a bridge of low reluctance connecting said yokes. 100
4. A loading unit core structure comprising two toroidal core members, yokes of low reluctance between said members at diametrically opposite points, and a bridge of low reluctance connecting the mid-portions of said yokes. 105
5. A loading unit comprising two toroidal core members, windings on each core on different sections thereof, yokes of low reluctance connecting said cores at points between said windings, and a bridge of low reluctance connecting said yokes. 115
6. A loading unit core structure comprising two toroidal core members, and bridging means of low reluctance connecting said members at diametrically opposite points and also connecting said points of each member. 120
7. A loading unit adapted for use with two physical circuits and a derived phantom circuit comprising two circumferentially complete core members, one for each physical circuit, means providing for the passage from each of said cores to the other of flux due to current in the phantom circuit, and means for diverting from each core flux from 125
- 65 130

the other core due to the current in the physical circuit with which it is associated.

8. A loading unit adapted for use with two physical circuits and a derived phantom circuit comprising two circumferentially complete core members, one for each physical circuit, means providing magnetic paths between said core members, and a magnetic shunt connecting said paths.

10 9. A device for magnetically connecting a pair of circumferentially complete loading unit cores comprising, in addition to said pairs of cores, two core-connecting members and a third member connecting said core-connecting members.

10 10. A loading unit core structure comprising two circumferentially complete core members, yokes of low reluctance between said members at diametrically opposite points, and a bridge of low reluctance connecting said yokes.

11. A loading unit core structure comprising two circumferentially complete core members and bridging means of low reluctance connecting said members at diametri-

cally opposite points and also connecting said points of each member.

12. A loading unit adapted for use with two physical circuits and a derived phantom circuit comprising two core members, each 30 one forming the major portion of a magnetic circuit for its physical circuit, means providing magnetic paths between said core members, and a magnetic shunt connecting said paths.

13. A loading unit adapted for use with two physical circuits and a derived phantom circuit comprising a pair of core members for each physical circuit, means providing for the passage from each of said pairs to 40 the other pair of flux due to current in the phantom circuit, and additional means for diverting from each pair flux from the other pair due to current in the physical circuit with which it is associated.

In witness whereof, I hereunto subscribe my name this 28th day of August, A. D. 1918.

WILLIAM FONDILLER.
